(57) CLAIM

The ornamental design for a trailer hitch insert, as shown and described.

DESCRIPTION

FIG. 1 is a perspective view of the trailer hitch insert, showing my new design;

FIG. 2 is a left side view of the trailer hitch insert thereof;

FIG. 3 is a right side view of the trailer hitch insert thereof;

FIG. 4 is a back view of the trailer hitch insert thereof;

FIG. 5 is a front view of the trailer hitch insert thereof;

FIG. 6 is a top view of the trailer hitch insert thereof; and,

FIG. 7 is a bottom view of the trailer hitch insert thereof.

The broken line showing of environment is for illustrative purposes only and forms no part of the claimed design.
